UNITED STATES PATENT OFFICE.

EDWARD J. WATTS, OF OAKLAND, CALIFORNIA.

DESIGN FOR A SHOW CASE.

Application filed August 16, 1927. Serial No. 23,103. Term of patent 7 years.

To all whom it may concern:

Be it known that I, EDWARD J. WATTS, a citizen of the United States, residing in the city of Oakland, county of Alameda, and State of California, have invented a new, original, and ornamental Design for a Show Case, of which the following is a specification, reference being had to the accompanying drawing, forming a part thereof.

Fig. 1 is a front view of a show case illustrating my new design; and

Fig. 2 is a side view of the same.

I claim:

The ornamental design for a show case as shown.

EDWARD J. WATTS.
